ELECTRIC SWITCH CONSTRUCTION

Kenneth C. Allison, Crystal Lake, Ill., assignor to
 Grigsby-Allison Co. Inc., Chicago, Ill., a corporation of Illinois

Application December 6, 1945, Serial No. 633,153

6 Claims. (Cl. 200—11)

1

This invention relates to electric switches and particularly switches of the type wherein contact arms which are carried by a rotor turning with a central shaft or spindle engage selected pairs of axially opposed contacts which are circularly arranged on a stationary member such as in switches applicable for controlling wireless receiving apparatus.

One object of the invention is the provision of a novel and improved construction of a switch for use in small radios, small consoles, portable radios, table models, and the like, wherein the use of a compact, relatively small dimensioned switch is especially desirable.

A further object of this invention is a novel and improved switch of the type referred to which is characterized by its simplicity in construction and assembly and the economy with which it may be manufactured in quantity production.

Other objects and advantages of the invention will become apparent from the following detailed description taken in connection with the accompanying drawings, in which:

Fig. 1 is a rear view of a switch embodying the present invention.

Fig. 2 is a side elevational view thereof.

Fig. 3 is a front view of the stationary member forming the rear wall of the switch.

Fig. 4 is an enlarged fragmentary vertical section taken on line 4—4 of Fig. 1.

Figs. 5 and 6 are rear views of the switch assembly with the stationary member and rotor removed to illustrate details of construction and arrangement of components defining a fixed index through which the rotated position of the rotor is controlled.

Figs. 7 and 8 and 9 are enlarged detail views of the rotor contact arms when in operatively supported position on the rotor member.

Fig. 10 is an enlarged detail view of the rotor contact member while in the process of attachment to the rotor member.

Fig. 11 and Fig. 12 illustrate a method of fastening the stationary contact members to the stationary member.

Fig. 13 is a detailed view of an opening for the reception of the contact member before the latter is fastened to the stationary contact member as indicated in Figs. 11 and 12.

Figs. 14 and 15 illustrate a switch of the type contemplated by this invention but embodying a housing of modified form.

Fig. 16 is a front view of the rotor member with one of the contact arms removed to show details of one of the contact arm holding recesses.

2

Fig. 17 is a side elevational view similar to Fig. 2 but taken on a transverse plane.

Referring to the drawing, the present switch includes a central driving shaft or spindle 10 having a forward portion 11 adapted to project through an opening in a suitable panel (not shown) and arranged to carry a suitable operating knob (not shown). The inner or rear end of the shaft 10 is formed with flattened sides 12.

10 The switch housing or frame member constitutes a front plate 13. An externally threaded bushing 14 staked as at 15 to the edges of a central opening in the plate 13 provides a bearing in which the shaft 10 may rotate. The bushing 14 is formed with a hexagonal head 16 having opposite flattened edges thereof in abutment with the offset edge portions of the plate opening as at 17 to secure the bushing and plate against relative movement. An annular groove 18 formed in 15 the shaft 10 is adapted to contain a lock washer 19 which coacts with the forward edge of the bushing to limit movement of the shaft 10 axially rearward of a selected position as shown in Fig. 4. Withdrawal of the shaft 10 from this position is controlled by a spring disk-shaped member 20 staked as at 21 to the shaft. The member 20 is formed with a forward projection 22 which rides over detents 23 projecting from the rear surface of the plate 13 in a manner to index or locate the rotated positions of the shaft 10 and the contact carrying members more specifically described hereinafter. A pair of stops 24 and 25 struck up from the front plate 13 in the path of rotation of the spring member 20 selectively engage a tail 26 on the member 20 to limit the 20 arc of movement of the shaft 10.

30 The front plate 13 is provided with diametrically opposed rearwardly extending legs 27. A reduced rear end portion 28 on each of said legs is adapted to be passed through apertures formed at diametrically opposite sides of a circular stationary member or plate 30 formed of suitable material such as laminated paper base phenolic resin sheet. A shoulder 31 formed at the base or inner limits of the reduced end portion of each leg 27 of the plate 13 cooperates with the front side of the plate 30 at the leg receiving openings so as to maintain the plate 30 in fixed axially spaced position relative to plate 13.

40 The plate 30 is punched to provide a series of circularly spaced openings 32 near the outer periphery thereof. Each of the openings 32 is adapted to be fitted with a contact member 33 of L-shaped design. One leg of each member 33 is offset intermediate its length to form a shoulder as at 34 adapted to bear against the front 45

50

surface of the plate 30 at the associated opening 32 to position the free end of the leg at a selected distance beyond the rear surface of the plate 30 to constitute a soldering lug portion, and the other leg of the member 33 is accordingly positioned at a selected distance beyond the forward surface of the plate 30. This position is fixed by a staked fastening as indicated at 35 and more particularly shown in Figs. 11, 12 and 13 and described in detail hereinafter.

A second series of circularly spaced openings 36 punched in the plate 30 in inward concentric relation to the openings 32 are designed to receive contact members 37. Each of the members 37, as shown in Fig. 3, constitutes a continuous contacting portion 38 coextensive with an arc defined by three (or another selected number of) successively arranged contact members 33. Staking of the members 37 as at 39, in the manner of the fastening applied to the members 33 shown in Figs. 11, 12 and 13, serves to rigidly position the contacting portion 38 with its rearward surface in engagement with the front side of the plate 30 and its forward surface in spaced rearward relation to the contact members 33 opposite thereto. This staking also serves to position the free end of the member 37 projecting rearwardly of the plate 30 at such a distance from the plate 30 as to constitute a soldering lug portion similar and in radially inwardly spaced relation to the corresponding portion of members 33.

A rotor plate 40 of insulating material like that of plate 30, is provided with a non-circular central opening conforming to the cross-sectional contour of the flattened end portion of shaft 10 whereby the rotor may be mounted on shaft 10 inwardly of plate 30 and rotatable with shaft 10 while free to move a limited distance axially of the shaft.

Contact members carried by the rotor 40 for cooperation with selected pairs of axially spaced contact members 33 and 37 of the stationary plate 30, each comprises a U-shaped resilient metal strip or member having a pair of arms 41 and 42 connected as at 43 at one end thereof. The connected end 43 is of such width as to present inwardly offset lateral edges 44 adapted to slidably engage the side or radial edges 45 and 46 of the notch in the rotor near the corners defined by said radial edges 45 and 46 of the notch and a transverse edge 47 at the inner limits of the notch when the connected end 43 is swung or moved in the plane of the rotor to an operative position as shown in Fig. 7 from a position as shown in Fig. 10. An offset portion 48 provided in the edge 46 of the notch is accordingly operative to trap the connected end 43 of the arms 41 and 42 against withdrawal from the notch in directions radially of the shaft 11 on which the rotor 40 is mounted. As shown in Fig. 9 the arms 41 and 42 diverge in a direction away from the connected ends and as shown in Fig. 7 are of such width as to respectively overlie the edges 45 and 46 of the notch and of such length as to extend a distance short of the periphery of the rotor.

An extension or tongue formed at the outer end of the arm 42 projects through and slidably engages the edges of the rotor notch when the connecting member 43 is in operative position, as shown in Fig. 8, and ears 49 projecting laterally from the free end of the tongue are engageable by the upper surface of the rotor at opposite sides of the notch to limit movement of the tongue

away from a position in engagement with the side edges of the notch. The outer end of the arms 41 and 42 are provided with bowl-shaped enlargements 50 and 51 respectively which present surfaces engageable with the inwardly opposed surfaces of corresponding pairs of contacts 33 and 37 on the stationary plate 30. It will be observed in Fig. 10 that the arms 41 and 42 as well as the tongue at the outer end of arm

42 may be flexed apart so as to clear the corner defined by the edge 46 of the notch and the outer edge of the rotor 40 to accommodate lateral swinging movement of the connecting member 43 about one edge 44 thereof positioned between the stop 48 and the side edge 46 between the offset or stop 48 and the inner limits of the notch in the rotor as a pivot, as shown in Fig. 10, toward and away from a position wherein the edges 44 of the connecting member 43 are in operative position between the edges 45 and 46 of the notch, as shown in Fig. 7.

It will be observed that inasmuch as the opposite edges 45 and 46 of the notch provide a fulcrum with respect to which the arms 41 and 42 of the contact member may move, the contact members on the rotor plate 40 may rock in a self-aligning manner relative to the contacts carried by the stationary member 30. Positive engagement of the surface portions presented by the bowl shaped enlargements 50 and 51 with respect to the contacts on the stationary member is further assured by the yieldable resistance of the arms 41 and 42 to move toward each other under pressure applied by the contacts on the stationary member.

As shown in Figs. 11, 12 and 13, the method of securing the contact members in rigid relation to the stationary member utilizes the added holding power of a fastener having a cross-sectional contour corresponding to that of a narrow strip of sheet metal, and an opening 32 of such cross-sectional form as to initially freely admit entrance of the strip therethrough and thereafter causing the strip to become forcibly jammed therein as the strip is progressively moved into a final seated position therein. The essential features of this type of fastening comprises an opening 32 in the member 30, as shown in Fig. 13, having relative dimensions a' and b' , and a member corresponding to member 33 shown in Figs. 11 and 12, having a head portion 34, and a neck or shank portion of uniform thickness b , a major dimension a adjoining the head portion 34 and a minor dimension c at its leading end. Dimension a being greater than a' , and dimension b being greater than b' and dimension c being less than a' , the member 33 when initially inserted in the opening 32 approaches a position of mating engagement with the corners at the entering end of the opening 32 and thereafter operating to distort said corners at the entering end. The staking developed as at 35 in Fig. 11 serves to laterally spread the edges of the member 33 from a position clear of to a position wherein said edges distort the corners at the discharge end of the opening 32. Thus the member 33 is seated solidly against the rear and front sides of the member 30 without the use of rivets or other separate fastening devices. The extreme simplicity with which this method of securing the contact members 33 in the stationary member 30 may be carried out thus greatly reduces the cost of providing a fastening having great holding power.

Figs. 14 and 15 illustrate a switch embodying

the features of this invention in conjunction with a front plate 55 of a cup shape cooperating with a rear plate 56, said plates being secured together by means of a series of inwardly bent tongues 57.

The present invention may be embodied in other specific forms without departing from the spirit or essential characteristics thereof. The embodiments contained herein are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed is:

1. An electric switch comprising a stationary member, a shaft mounted for rotation about a fixed axis and in central perpendicular relation to the general plane of said stationary member, a rotor mounted for rotation with said shaft, radially extending notches provided in the periphery of the rotor, each notch having a U-shaped resilient contact member trapped therein to secure said contact member against movement relative to said notch in directions radially of the shaft, said U-shaped contact member providing axially aligned contact arms in radial relation to said shaft and diverging in a direction away from said shaft, and axially spaced pairs of rigid contact arms on said stationary member presenting inwardly opposed surfaces with which said rotor contacts are slidably engageable.

2. An electric switch as claimed in claim 1 wherein said U-shaped contact members on the rotor have limited swinging movement relative to the rotor in directions axially of said shaft about edge portions of the notch defining the inner limits of said notch.

3. An electric switch as claimed in claim 1 wherein said U-shaped contact members on the rotor have swinging movement relative to the rotor in directions axially of said shaft about edge portions of the notch defining the inner limits of said notch, and said diverging arms are disposed to respectively overlie opposite edge portions of the notch intermediate the inner and outer limits of said notch.

4. In an electric switch, the combination of a flat insulated support having a radially extending notch formed in the periphery thereof, a U-shaped resilient member confined in said notch with the arms thereof extending toward but a distance short of the periphery of said support and in divergent relation to opposite faces of the support in a direction away from the inner limits of said notch, and means engageable with the connected ends of said arms to trap the U-shaped resilient member in operative confinement in said notch including an offset portion formed in one of the radially extending edges of said notch.
5. In an electric switch as claimed in claim 4 wherein swinging movement of the arms toward and away from the opposite faces of the support is limited by means including an extension of one of said arms projecting through said notch toward the other of said arms.
6. In an electric switch as claimed in claim 4 wherein swinging movement of the arms toward and away from the opposite faces of the support is limited by means including an extension of one of said arms projecting through said notch toward the other of said arms, said extension being flexible to pass the corner defined by the periphery of the support and the radial edge of the notch about which the U-shaped member is swung in the plane of the support while the connected ends of the arms are engaged by the offset portion aforesaid as a fulcrum incident to completing assembly of the support and said U-shaped member.

KENNETH C. ALLISON.
